AWNING CONSTRUCTION

Filed Oct. 31, 1929

2 Sheets-Sheet 2

UNITED STATES PATENT OFFICE

GEORGE SCHULER, OF WOODSIDE, NEW YORK

AWNNG CONSTRUCTION

Application filed October 31, 1929. Serial No. 403,707.

This invention relates to awning construction and has for one of its objects the provision of an awning that may readily be operated from the inside of the house without removing the wire screen that may be in place in the window frame.

Another object of the invention is to provide an awning suspension frame that may readily be removed from its anchorage without removing the awning curtain therefrom.

A further object of the invention is to provide a spring roller awning with means to overcome the force of the wind and prevent same from blowing the awning up and down and thus damage the awning.

A still further object of the invention is to provide an awning having telescopically arranged and pivotally mounted awning curtain extension means, the said extension means being adapted to swing an equi-angular distance on each side of its pivotal center, and means to so limit the said movement.

Another object is to produce a device of the character described in which the maximum simplicity of construction and operation is secured.

Other objects and advantages will appear as the nature of the improvements is better understood, the invention consisting substantially in the novel arrangement and co-relation of parts herein fully described, and illustrated in the accompanying drawings, wherein similar reference characters are used to describe corresponding parts throughout the several views, and then finally pointed out and specifically defined and indicated in the appended claims.

The disclosure made the basis of exemplifying the present inventive concept suggests a practical embodiment thereof, but the invention is not to be restricted to the exact details of this disclosure, and the latter, therefore, is to be understood from an illustrative, rather than a restrictive standpoint.

The inventive idea involved is capable of receiving a variety of mechanical expressions, one of which, for the purpose of illustration, is shown in the accompanying drawings, in which:—

Figure 1 is a front view in elevation of my

improved awning, looking from the outside of the house;

Figure 2 is a vertical sectional view taken on line 2—2, Fig. 1;

Figure 3 is a sectional view of the awning suspension frame taken on line 3—3, Fig. 2;

Figure 4 is a side view of the awning partly extended, looking from the right of Figure 1 and showing means for preventing a gust of wind from unrolling the awning curtain.

Figure 5 is a similar view to Figure 4 showing a wing secured to the suspension frame and the outer member of the telescoping curtain extension frame, to prevent the wind from unrolling the awning.

Figure 6 is a fragmental detail view of a portion of the curtain extension means.

Figure 7 is a sectional view taken on line 7—7, Figure 5 showing one of the wing securing members, and

Figure 8 is a perspective view of the inner roller carrying and awning rope fastening bracket.

Referring to the drawings in detail, 10 indicates a window frame provided with side members 11 and 12, and top and bottom members 13 and 14 respectively, and mounted in the said frame are the usual top and bottom sashes 15 and 16 as well as a wire screen 17.

Secured to the member 13 there are a pair of brackets 18 from which there is suspended an awning suspension frame 19 carrying a spring roller 20 to which is secured one end of an awning curtain 21. The free or opposite end of the said curtain is provided with a fold or pocket 22 through which passes and is secured therein a rod or tube 23. Brackets 24 and 25 are secured to the side members 11 and 12 respectively and have pivotally mounted in them hollow rods or tubes 26 in which tubes there are telescopically arranged rods 27 provided with flattened ends or ears 28 rotatably mounted on the curtain rod 23. The free end of the curtain is further provided with an eye bolt 30 to which is secured a cord 31 passing around a pulley 32 mounted on a bracket 33 which is secured to the screen 17. The cord 31 then passes inwardly through a bushing 34 in the screen 100

and thence around a second pulley 35 mounted on a bracket 36 provided with a cutout 37 forming a cleat-like structure around which the cord may be wound when the awning is extended.

5 The curtain suspension frame 19 is provided with a pair of base plates 40 having slots 41 through which pass studs or bolts 42 which thread into the window frame 10 to 10 removably maintain the awning suspension frame in place. As will be seen by referring to Figures 2 and 3 of the drawings, the suspension frame and awning may readily be removed from the window frame by turning 15 the bolts 42 so that the heads of the said bolts are parallel to the slots 41, in which position the frame carrying the spring roller with the awning curtain thereon can be readily lifted off the brackets 18.

20 Usually in awnings of this nature the rod in the free end of the curtain is provided at its ends with cotter pins or nuts to maintain the curtain extension device thereon, this method is often very unsatisfactory as these pins or nuts become loose and are entirely lost. To overcome this difficulty and disadvantage I rivet studs 45 (see Fig. 6) into the ends of the rod 23, the heads 46 of which studs project into the path of the flattened 25 portions 28 and prevent same from slipping off the rod 23. The flattened portions 28 are each provided with a groove 47 to permit the rods 27 to be assembled on the rod 23.

It will be understood that when the awning 30 is partly extended the cord 31 when tied down prevents the awning from rolling up, but a sudden gust of wind may exert sufficient force to unroll the awning curtain and flap same down and then up again and thus 35 loosen the entire structure. To overcome this I have shown in Figure 4 a strip 50 which may be made of any suitable material. A pair of these strips may be used for each awning and each strip may be secured at one end to the sidewalls of the suspension frame 19 and at its opposite end to the rod 23 by any suitable means, such as for instance wire links 40 51 and 52. In Figure 5 I have shown a modified form of the above arrangement, 45 wherein I employ an awning wing 54 on each side of the awning and secure the said wings at the upper end to the frame 19 by means of fastenings 55 and at the lower end I secure same at the rear end to the bracket 25 and at the forward end to a securing member 56 on the tubular member 26.

The operation of my improved awning is as follows: The spring roller 20 with the awning curtain 21 carrying the rod 23 and 50 extension rods 27, is mounted in the frame 19 which is then suspended from the brackets 18 and secured by means of the studs 42. The outer tubular members 26 are slipped over the inner members 27 and pivotally secured to the brackets 24 and 25. The rope or cord 31

is passed around the pulleys 32 and 35 and the awning is adjusted or extended to any desired position.

As shown in Figure 2, when the awning is fully rolled up the tubular members 26 engage or abut extensions 26^a and when fully unrolled they abut extensions 26^b on the brackets 24 and 25 thus preventing the telescoping curtain extension means from reaching a locking or dead line position.

70 The awning curtain may if desired be provided with an apron or extension 58 secured to the fold or pocket portion 22 which may be folded over same that it may roll around the roller when the awning is fully retracted or rolled up.

75 From the foregoing it will be seen that I have provided a simple and efficient awning adapted to be readily mounted and demounted, and provided with means to prevent same to be flapped about by the wind when partly extended and further provided with means to prevent same from being operated to a dead center line or locking position when fully extended or retracted.

80 Having described my invention, what I claim as new and desire to secure by Letters Patent is:—

85 1. In an awning adapted for use over a window or door frame, an awning suspension frame having openings therein, a pair of brackets, adapted to extend through the said openings to removably support the said frame, slotted extensions on the frame, and headed frame securing bolts adapted when in 90 one position to secure the suspension frame in place through the said slots, and when partly rotated to so position the head to permit the frame to be lifted off its support.

95 2. In a window awning, a frame, a spring roller operably supported therein, an awning curtain secured at one end to the roller, a rod-like member secured to the opposite end of the curtain, telescopically arranged 100 curtain extension members in engagement with the rod-like member, and a strip secured to the frame and the rod-like member for the purpose specified.

105 3. In a window awning, a frame, a spring roller operably supported therein, an awning curtain secured at one end to the roller, a rod-like member secured to the opposite end of the curtain, telescopically arranged 110 curtain extension members in engagement with the rod-like member, and awning wings secured to the frame and the extension members for the purpose specified.

115 4. In an awning having a curtain extension member, a bracket upon which the said member is swingingly mounted, and extensions on the said bracket to engage the said extension member to limit the movement thereof in extension and retraction direction.

120 5. In an awning having a curtain extension member, a bracket upon which the said mem-

ber is swingingly mounted and an extension on the said bracket for the purpose specified.

5 6. In an awning having a rod-like member in the free end thereof, a slotted curtain extension member for operative engagement with the said rod-like member, and a projection on the said member for the purpose specified.

10 7. In an awning having a rod-like member in the free end thereof, a pair of slotted curtain extension members in operative engagement with the said rod-like member near its ends, and a projection near each end of the said member for the purpose specified.

15 In testimony whereof I hereunto affix my signature.

GEORGE SCHULER.
